UNITED STATES PATENT OFFICE.

DUNCAN M. RUSSELL AND JAMES BUCHANAN, OF WALSENBURG, COLORADO.

SLACK TAKE-UP DEVICE.

Application filed February 3, 1925. Serial No. 6,595.

This invention relates to slack take-up devices and more particularly to a device of this character primarily intended for use in connecting brake levers and brakes.

An important object of the invention is to provide means whereby the connection between the lever and objective is shortened during the working stroke.

A further object of the invention is to provide a device of this character in which, when the working stroke exceeds a predetermined length, the connection is held in its shortened position so that the next succeeding working stroke will be shortened.

A still further object of the invention is to provide means whereby the element accomplishing the shortening will automatically take-up as to length so as to remain at all times at the proper length for the distance through which it must operate.

A further and more specific object of the invention is to provide a connection between the lever and objective including a rotatable part which, when rotated, varies the effective length of the connection and the connection between the rotatable part and lever partially rotating the same upon each operation of the lever.

A still further object of the invention is to provide means for preventing return motion of the rotatable part when this motion exceeds a predetermined amount and at the same time shortening the connection between the rotatable part and the lever so that it remains of the same or proper effective length.

These and other objects we attain by the construction shown in the accompanying drawings, wherein for the purpose of illustration is shown a preferred embodiment of our invention and wherein:—

Figure 1 is a side elevation of slack take-up mechanism constructed in accordance with our invention applied to connect a lever and brake;

Figure 2 is a plan view thereof;

Figure 3 is an enlarged detailed view of the central take-up mechanism, one of the side ends being removed;

Figure 4 is a detailed sectional view of the take-up mechanism of the link 16; and

Figure 5 is a side elevation of a modified form of the invention.

Referring now more particularly to the drawings, the numeral 10 indicates a lever pivoted at one end as indicated at 11, and

12 a brake or other element to be operated from the lever and to be moved to operated or set position by movement of the lever in the direction of the arrow A of Figure 1. 60
The connection between the lever and member to be operated comprises primarily a link 13 connected with the lever, a link 14 connected with the member, a rotatable connection 15 between adjacent ends of the links 13 and 14 which, when rotated, varies the effective overall or combined length of the links 13 and 14 and a connection 16 between the lever 10 and the member 15 whereby the member 15 is partially rotated upon each 70 operation of the lever. The connection 16 is engaged with the lever 10 at a point 17 spaced longitudinally of the lever from the point of connection of the link 13 therewith. In the present instance, this connection 75 is disclosed as being remote from the pivot 11 of the lever 10 with respect to the point of connection of the link and accordingly the connection 16 moves through a greater distance upon operation of the 80 lever 10 than the link 13 will move, thus providing the extra motion necessary to rotation of the rotating part 15. It will, however, be obvious that the connection 16 could be engaged with the lever 10 between 85 the pivot 11 and the point of engagement of the link 13 therewith and still provide this difference of distance of operation necessary to accomplish rotation of the member 15. The connection disclosed is, however, 90 preferred for the reason that with a connection such as last described, a thrust in opposition to the direction of movement of the lever is set up decreasing the efficiency 95 of operation.

In addition to the foregoing structure, means are provided for preventing return rotation of the member 15 when this rotation has exceeded a predetermined amount. In the present construction, the rotating member 15 is provided with an arcuately curved face 18 formed with ratchet teeth 19 of a desired length and the link 14 has pivotally engaged therewith a dog 20 for coaction with these ratchet teeth. In the present construction, the link 14 is shown as having its forward end bifurcated to form arms 21 between which the rotating member 15 extends and by which the pivot dog 20 is supported. This link 14 is preferably 105 formed of two sections 22 and 23, the first of which bears the arms 21 while the latter 110

is provided at its rear end, as at 24, with means for engagement with the brake. These sections have their adjacent ends connected by a turn buckle 25.

- 5 The link 13 is provided at its rear end with an eccentric strap 26 receiving an eccentric 27 carried by and pivoted between the forward ends of the arms 21 of the section 22 of the link 14, as at 28. The pivotal 10 connection with the eccentric is spaced from the center of the eccentric and accordingly upon rotation of the eccentric, the effective length of the links 13 and 14 and the connection therebetween will be altered. To the 15 side of this eccentric are secured plates 29 the peripheries of which are formed with the arcuately curved faces 18 and teeth 19 for coaction with the latch dog 20. These plates are further provided with a pair of 20 opposed ears 30 pivotally receiving therebetween the rear end of the link 16, as at 31. The link 16 is formed in two sections 32, 33, the former being engaged with the lever 10 and the latter with the ears 30. 25 The section 33 has its forward end in the form of a tube 34 slidably receiving the rear end of the section 32. The section 32 is provided with ratchet teeth 35 and the tube 34 with a pawl 36 for coaction with these 30 ratchet teeth. In the form shown in Figure 5, the link 13 instead of being provided upon its rear end with the eccentric strap 26 is pivotally secured, as at 37, to a disk 38 at a point adjacent the periphery of this disk 35 while the forward ends of the arms 21 are pivotally engaged with the disk at the axis thereof, as indicated at 39. The rear end 33 of the link 16 is pivotally engaged with the periphery of the disk, as at 40, and this 40 periphery is formed with the teeth 19 for coaction with the dog 20 of the link 14.

The operation of the device is as follows:— When the lever 10 is moved in the direction of the arrow A, the links 13, 14, are shifted 45 in this direction a distance proportionate to the degree of movement of the lever. At the same time, the link 16 by its engagement with the periphery of disk 29 or single disk 38 will cause a rotation thereof in the 50 direction of the arrow B of Figure 1, and this rotation will likewise be proportionate to the amount of movement of the lever. If the lever 10 is moved through a predetermined distance, the dog 20 will pass over the shoulder of one of the teeth 19 and will prevent return motion of the rotatable member 15 and retain the links 13 and the connection represented thereby in their shortened relation. When the lever is returned 55 to its normal position, as in a majority of structures, it is returned by a spring, it will be obvious that the section 32 of the link 16 will move into the tube 34 and this link 60 will have its sections maintained in this shortened relation by the engagement of the 65

dog 36 with the teeth 35. This shortening movement will continue until the two sections of the rotating member 15 and link 16 have been taken up.

It will, of course, be obvious that it is not contemplated that such an operation shall take place at each operation of the lever 10 but that it shall only take place when the lever 10 is moved to its fullest extent. Thus in the operation of a brake, the length of the teeth 19 will be so computed that this operation only takes place when the lever 10 has been moved to practically the fullest extent possible. When the two sections have been completely taken up, the dogs 36 and 20 are released and the parts permitted to return to the position where the links 13, 14, have their greatest overall length. The link 14 is then shortened as to effective length by use of the turn buckle, thus returning the apparatus to its original condition. Contemplation of the structure of Figure 5 will render it obvious that instead of the disk employed, an ordinary crank could be employed with equal facility but since pivoted disks have long been considered as the equivalent of a crank when connected, as disclosed, no illustration of this structure has been made.

Other advantages and modifications being possible in the structure hereinbefore set forth, we do not limit ourselves to such specific structure except as hereinafter claimed.

We claim:—

1. A slack take-up connection between a lever and a member to be shifted thereby including a link connected with the lever, a second link connected with the member, a connection between the first and second links rotatably engaged with each thereof and when rotated, varying the combined overall length of the links and a third link connecting the rotatable member and lever at a point spaced longitudinally of the lever from the point of connection of the first named link therewith.

2. A slack take-up connection between a lever and a member to be shifted thereby including a rotatable part which, when rotated, varies the effective length of the connection, a connection between the rotatable part and lever partially rotating the same upon each operation of the lever, means for preventing return rotation of the rotatable part when the same has been rotated a predetermined distance and means for varying the length of the connection between the rotatable part and lever to compensate for the shifting of the rotatable part.

3. A slack take-up connection between a lever and a member to be shifted thereby including a link connected with the lever, a second link connected with the member, a connection between the first and second

links rotatably engaged with each thereof and when rotated, varying the combined overall length of the links, and a third link connecting the rotating member and lever at a point spaced longitudinally of the lever from the point of connection of the first named link therewith, said link being formed in two sections telescopically engaged and having ratchet engagement with one another.

4. A slack take-up connection between a lever and a member to be shifted thereby including a rotating part which, when rotated, varies the effective length of the connection, and a connection between the rotatable part and lever partially rotating the same upon each operation of the lever, comprising a link formed in two sections telescopically engaged and having ratchet connection with one another.

5. A slack take-up connection between a lever and a member to be shifted thereby including a link connected with the lever, a second link connected with the member, a member rotatably engaged with the free end of the first named link and with which the second link is rotatably engaged at a point spaced from the point of connection of the rotatable member with the first named link and a third link pivotally engaged with the rotatable member at one end and at its opposite end with the lever.

6. A slack take-up connection between a lever and a member to be shifted thereby including a link connected with the lever, a second link connected with the member, a member rotatably engaged with the free end of the first named link and with which the second link is rotatably engaged at a point spaced from the point of connection of the rotatable member with the first named link, a third link pivotally engaged with the rotatable member at one end and at its opposite end with the lever, said rotatable member being provided upon its periphery with ratchet teeth, the second link having a dog for coaction with said ratchet teeth and

means for automatically shortening the third link to compensate for changes of position of the point of its connection with the rotatable member with respect to the lever.

7. A slack take-up connection between a lever and a member to be shifted thereby including a link connected with the lever, a second link connected with the member, a member rotatably engaged with the free end of the first named link and with which the second link is rotatably engaged at a point spaced from the point of connection of the rotatable member with the first named link, a third link pivotally engaged with the rotatable member at one end and at its opposite end with the lever, said rotatable member being provided upon its periphery with ratchet teeth, the second link having a dog for coaction with said ratchet teeth and means for automatically shortening the third link to compensate for changes of position of the point of its connection with the rotatable member with respect to the lever, the third link being formed in two sections, said compensating means including a dog carried by one of the sections and engaging ratchet teeth formed upon the other of the sections.

8. A slack take-up connection between a lever and a member to be shifted thereby including a rotating part which when rotated, varies the effective length of the connection, a connection between the rotatable part and lever partially rotating the same upon each operation of the lever, means for preventing return rotation of the rotatable part when the same has been rotated a predetermined distance, means for varying the length of the connection between the rotatable part and lever to compensate for the shifting of the rotatable part and manually operable means for varying the effective length of the connection.

In testimony whereof we hereunto affix our signatures.
